UNITED STATES PATENT OFFICE.

WILLIAM J. TOMPKINS, OF MOUNT VERNON, NEW YORK.

METHOD OF MAKING RESILIENT HEEL LIFTS.

Application filed June 10, 1921, Serial No. 476,421. Renewed August 1, 1924.

To all whom it may concern:

Be it known that I, WILLIAM J. TOMPKINS, a citizen of the United States, and resident of the city of Mount Vernon, in the county of Westchester and State of New York, have invented certain new and useful Improvements in Methods of Making Resilient Heel Lifts, of which the following is a specification.

This invention relates to resilient heel lifts. In the familiar type of flat rubber heel lift, as distinguished from the concavo-convex type, it is a well known fact that a tight fitting contact of the marginal edges of the lift, at its attaching surface with the face of the leather heel, cannot be maintained and that in a short time the edges of the rubber lift will separate from the heel face. In order to overcome this objectionable feature of the flat type of heel lift, the concavo-convex lift has been devised. The concavo-convex lift most widely employed is provided with concentric attaching and tread surfaces, respectively concave and convex, and of semispherical curvature. In other words, this lift may be considered as a section of a hollow spherical body. It is manifest that when such a lift is flattened against a leather heel to bring its concave surface in contact therewith, the rubber is tensioned and the lift, tending to reassume its normal shape exerts a very tight frictional pressure at its marginal edges against the heel face. While the objection referred to is thus obviated in the concavo-convex type of lift, the use of such lifts as heretofore constructed also presents certain objectionable features.

One of the most objectionable of such features arises from the fact that it is not possible to completely flatten a spherical surface. Thus, when the concave surface of this lift is applied to the leather heel face and pressure exerted against the convex tread surface, a constantly increasing compressing action takes place on the convex side of the lift, while a corresponding expansive action takes place on the concave side of the lift. The lateral expansion of the lift at the face of the heel is strongly resisted by the constantly increasing tension and frictional pressure of the marginal edges of the lift against the leather heel. Therefore, the rubber stock of which the lift is formed is crowded inwardly so that the entire area of the concave surface does not come into

contact with the rubber heel, but is spaced therefrom, at different points, particularly between the fastening nails, which results in a corresponding protuberance or projection on the tread surface of the lift. Therefore, it is clear that when this type of lift is flattened and nailed or otherwise attached to the shoe heel, it will not have a flat or level tread face, all parts of which are located in a single horizontal plane. On the contrary, there will be produced an uneven tread surface so that the wearer experiences a sensation of insecurity. This type of heel also has another, more or less, serious objection in that the inward crowding pressure of the stock exerts an uneven lateral pressure against the fastening nails, which causes the nails to become loose. This is particularly evident in those cases where the rubber lift is applied to a shoe heel made of paper or other composition material, in which the nails do not hold as in leather. Heels of this construction are quite common in the cheaper grades of shoes.

It is, therefore, the primary object and purpose of the present invention to provide a method of producing a heel lift of the concavo-convex type in which the objections above noted are not present, which objections to a certain degree have been responsible for the rather limited use of this type of heel. In one embodiment of the invention I provide a heel lift made of rubber or other resilient material, the lift having a concave attaching surface, not necessarily semispherical, and a convex tread surface which is more or less eccentric to the concave surface, the lift having its smallest thickness at the central portion thereof and gradually increasing in thickness to the marginal edges. It will be at once seen that with a heel lift of this construction, when pressure is applied to the convex surface and the lift is flattened against the shoe heel and nailed or otherwise attached thereto, the rubber stock will crowd inwardly from the marginal edges of the lift, as in the old type of concavo-convex lift, but this inward crowding of the stock will merely equalize the thickness of the lift throughout its area and compensate for the thinness of the stock in the normal condition of the lift so that a depression or cavity will not form in the tread surface of the lift, but this tread surface will be absolutely level and flat and have all parts thereof disposed within a

horizontal plane, coinciding with the perimeter of the tread surface of the marginal edges of the lift.

In obtaining this improved result I have 5 evolved a method of ascertaining the particular degree of eccentricity of the tread surface with respect to the attaching surface of the lift, in accordance with which the molds are made for the production of the 10 improved lift.

With the above and other objects in view, the invention consists in the method of making heel lifts, as will be hereinafter more fully described, illustrated in the accompanying drawings and finally incorporated in the subjoined claims.

In the drawing wherein I have illustrated several desirable embodiments of the invention, and in which similar reference 20 characters designate corresponding parts throughout the several views,

Figure 1 is a perspective view of one form of the improved lift in its normal condition before application to the shoe heel.

25 Figure 2 is a longitudinal section taken on the line 2—2 of Figure 1.

Figure 3 is a transverse section taken on the line 3—3 of Figure 2.

30 Figure 4 is an elevation showing the lift applied to a shoe heel and illustrating in dotted lines the uneven tread of the old type of concavo-convex lift.

Figure 5 is a transverse section, showing a slightly modified form of the invention, 35 and

Figure 6 is a semidiagrammatic view illustrating the method of producing the improved lift.

Referring in detail to the drawing and 40 more particularly to Figures 1, 2 and 3 thereof, I have illustrated a lift of rubber or other resilient material having a concave attaching face substantially semispherical in shape. It is, however, not essential 45 that this attaching face or surface shall be of semispherical shape, since other shapes may be provided, the important consideration being that there shall be a sufficient concavity to produce a tight hugging action 50 of the entire marginal edge portion of the lift against the leather heel when the lift is applied and nailed thereto. In the drawing, the numeral 9 indicates generally a heel lift of this type having a convex tread face 55 10, and a concave attaching face or surface 11.

It will be noted from an examination of 60 Figures 2 and 3, that the tread surface 10 is not concentric with the concave attaching surface 11, but eccentric thereto. Thus the central portion of the lift as shown at 65 12, is relatively thin and the lift gradually increases in thickness from this central portion to its breast edge 13, and to its rear end 70 14, in a longitudinal direction. Likewise,

the lift gradually increases in thickness transversely thereof, from the central portion indicated at 12' in Figure 3 to the side marginal edges. It is to be understood from this description that at the rear end 70 of the lift, the thickness indicated between the lower and upper edges of the lift 15 and 17 respectively, is substantially the same as the thickness of the lift between its lower and upper edges 16 and 18 respectively at 75 the breast 13. Likewise, in Figure 3 of the drawing, the thickness at one side of the lift between the upper and lower edges 20 and 21 is substantially the same as the thickness between the lower and upper edges 22 and 23 at the opposite side of the lift. It will 80 thus be understood that the lift uniformly increases in thickness in opposite directions from its central portion outwardly to its marginal edges both longitudinally and 85 transversely of the lift.

In Figure 4 of the drawing I have shown the lift 9 applied to the leather heel 25 of the shoe 26 by means of the nails 27 or other equivalent fastening means. When pressure 90 is applied against the convex tread surface of the lift to flatten the same against the leather heel, as seen in Figure 4, it is apparent that the gradually increasing frictional pressure of the marginal portions of the lift against the heel face exerts a resisting influence against the lateral expansion of the lift, at its concave face, so that the rubber stock crowds inwardly towards the relatively thin central portion of the lift. Therefore, any hollow or depression in the tread face of the lift which might otherwise form is compensated for, so that when the lift is finally flattened and attached to the heel, the tread surface thereof is absolutely flat 100 and level with all portions disposed in a common horizontal plane, coinciding with the perimeter of the tread surface.

In Figure 4, I have indicated by means of the dotted lines 10' protuberances or projections which are produced upon the tread surface of the lift in the old type of lift where the concave and convex surfaces are concentric with each other. It will be noted that these projections of the tread surface occur particularly between the fastening nails and at these points, also the concave surface opposed to the heel face is spaced from the leather heel. This is caused by the inward crowding of the stock, the outward expansion of which is resisted by the great tensional pressure of the marginal portions of the lift against the heel.

In Figure 5 I have illustrated a slightly 125 different embodiment of the invention, wherein the lift is provided with a relatively shallow concave attaching surface 11' and a tread surface 10' which consists of a plurality of angularly related flat or plane surfaces. When this lift is applied to the 130

leather heel and the lift flattened to bring the concave surface 11' into contact throughout its area with the heel face, the tread surface 10^a is disposed slightly beyond or 5 inwardly of a horizontal plane, coinciding with the perimeter of said tread surface.

In other words, in this case, as in the preferred embodiment of the invention, no part of the tread surface projects beyond the 10 horizontal plane referred to, so that in neither case will the lift, when attached, present an uneven tread. In this last described form of the invention, the same tight hugging action of the marginal edges 15 of the lift against the face of the leather heel is secured, while all portions of the lift are located between true parallel horizontal planes, which respectively coincide with the perimeters of the attaching and tread surfaces. 20

In practice I have found that the necessary degree of eccentricity of the tread surface of the lift with respect to the attaching surface may be accurately ascertained 25 for the purpose of producing the molds whereby the lifts are manufactured, by attaching an old concavo-convex lift having concentric attaching and tread surfaces to a heel or other fixed part, as indicated in Figure 6, and then cutting off or planing down that portion of the tread surface of the lift which protrudes beyond the horizontal plane, coinciding with the perimeter of the tread surface at the margin of the lift. 30 This protruding part, which is cut from the lift, I have indicated at 10^b in Figure 6. When the lift is removed from the heel, it will then be found that the lift is relatively thin at its central portion and the tread surface is eccentric to the attaching surface, substantially as indicated in Figures 2 and 3. From the model thus produced templets are made in accurate conformity to the curvature of the concave and convex surfaces, 40 and by means of these templets the male and female die member of the mold can be accurately produced in the usual manner.

From the foregoing description, considered in connection with the accompanying 50 drawing, the form and construction of the improved heel lift and the manner of producing the same will be clearly understood. By means of the improved construction an absolutely level or flat tread surface is obtained when the lift is attached, and the objections to the old concavo-convex type of heel lift are wholly eliminated. While the 55 projections or protuberances on the tread surface of the heel lift of the old type are primarily due to the cause above referred to, these protuberances are accentuated by the 60 fastening nails exerting a compressing ac-

tion on the stock and tending to pull the tread surface down. It is somewhat difficult to accurately indicate this uneven appearance of the tread surface in the drawing, but it is quite evident in the use of the old type of lift. It will also be understood that in Figures 2 and 3 the illustration of the eccentric relation of the convex tread surface 65 to the concave attaching surface of the lift is more or less exaggerated. In the actual lift, the degree of eccentricity is very slight. However, it is sufficient to insure the engagement of the concave attaching surface 70 throughout its area with the leather heel when the lift is flattened and to compensate for the forces of compression and expansion 75 acting to crowd the rubber inwardly from the margin toward the central portion of 80 the lift.

As above stated, the particular shape of the concave attaching face of the lift is immaterial, and my present improvement may be carried out or produced in connection 85 with many different types of concavo-convex heel lifts known in the art. It is, therefore, to be understood that I do not desire to be limited to the specific forms herein illustrated, but reserve the privilege of adopting 90 all such legitimate changes as may be fairly embodied in the spirit and scope of the appended claims.

I claim:

1. A method of manufacturing resilient 95 heel lifts which consist in first flattening a concavo-convex resilient lift having concentric attaching and tread surfaces, then removing from the tread surface of the flattened lift all stock protruding beyond a horizontal plane coinciding with the perimeter 100 of the tread surface, then detaching the lift and making mold dies in accordance with the curvatures of the concave and convex surfaces of the modified lift and then producing resilient lifts by means of the mold dies, having convex surfaces conforming to 105 the corresponding surfaces of the modified lift.

2. In a method of manufacturing resilient 110 heel lifts the steps which consist in first flattening a concavo-convex resilient lift having concentric attaching and tread surfaces, then removing from the tread surface of the flattened lift all stock protruding beyond a horizontal plane coinciding with the perimeter 115 of the tread surface, and making mold dies in accordance with the curvatures of the concave and convex surfaces of the modified lift.

In testimony that I claim the foregoing as my invention, I have signed my name hereunder.

WILLIAM J. TOMPKINS.
